UNITED STATES PATENT OFFICE

1,925,556

MOTOR-COMPRESSOR UNIT

Ransom W. Davenport, Detroit, Mich., assignor
to Chicago Pneumatic Tool Company, New
York, N. Y., a corporation of New Jersey

Application February 27, 1929. Serial No. 343,177

5 Claims. (Cl. 230—207)

This invention relates to apparatus used in the transforming of heat and particularly concerns means for freeing vaporized refrigerant from entrained lubricant. While of general utility it has direct application to refrigerating systems of the closed cycle type in which the lubricant used is partially or fully soluble in the refrigerant. It has been developed and is specially intended for use in systems operating in accordance with the process disclosed in my Patent No. 1,698,938, issued January 15, 1929. More specifically it concerns the dynamic means for circulating the refrigerant solution.

One object of the invention is to provide an improved pump or compressor unit which is particularly adapted for a lubricant which is soluble in the working medium or refrigerant. Another object is to secure adequate lubrication of the moving parts of the apparatus without impairing the heat transforming effects of the system, and vice versa. Other important objects will be apparent from the detailed description which follows.

In a refrigerating system operating in accordance with the process set forth in my patent above identified, a solution of lubricating oil in refrigerant liquid is alternately concentrated and diluted while evaporating to absorb heat and condensing to eject heat, respectively. The lubricant and the volatile refrigerant are caused to vary in their respective proportions. In the pump the solution should be practically all lubricant while in the refrigerating evaporator the solution should be practically all volatile liquid. As volatile liquids are "thin" and of low viscosity and film strength, they are not suitable as lubricants for the purpose of floating bearings or for sealing clearance spaces. Furthermore, as the vapor tension of liquids suitable for refrigeration is rather high, any considerable proportion of refrigerant in the lubricant in the compressor would result in transferring the refrigerating effect from the evaporator to the compressor itself.

Any suitable methods and apparatus may be used for concentrating the solution sufficiently to use the same for lubricating purposes before the solution reaches the pump. But to maintain the lubricant at proper viscosity in the pump, the lubricant must be kept away from contact with the vapor of the volatile liquid at all temperatures below the maximum occurring at the discharge port of the compressor. It is, therefore, a particular object of the present invention to combine apparatus for compressing the vapor

and at the same time maintaining the viscosity of the lubricant at a satisfactory high point.

According to the present invention, the pump is provided with means for keeping the lubricant and the refrigerant vapor, discharged together by the pump, so far as possible out of heat exchanging relationship with the pump and with other apparatus while the suspended oil is being separated. The invention also provides for collecting and distributing the separated lubricant to the parts requiring lubrication while moving the hot vapor directly to the condenser and away from the lubricant. By preference the motive agent for the pump, such as an electric motor, is mechanically connected with the pump by way of a single common shaft and is also pneumatically and hydrostatically combined with the separating means and with the pump, the entire combination being sealed so as to afford a wholly self-contained machine or unit suitable for use in mechanical refrigerating systems of the closed cycle compression type.

In order to illustrate the invention one concrete embodiment thereof is shown in the accompanying drawing, in which:

Fig. 1 is a longitudinal sectional view through a totally enclosed and sealed motor pump unit;

Fig. 2 is a transverse sectional view through the pump portion of the unit substantially on the line 2—2 of Fig. 1;

Fig. 3 is a right end elevational view of the pump alone and indicates diagrammatically the manner of connecting the same into a compression refrigerating system; and

Fig. 4 is a fragmentary sectional view of the motor pump unit shown in Figs. 1 and 2, the sectioned portion of the pump being indicated by the broken line 4—4 of Fig. 3.

In the embodiment of the invention chosen for the purpose of illustration, a rotary pump of the stationary abutment or blade type is shown, but it is to be understood that the particular type of pump has no relation to the spirit of the invention since a reciprocating piston pump could be used to equal advantage. The rotary pump A is combined with electrical motor B to form a totally enclosed and sealed motor pump unit, which comprises pump casing 5, closure member 6, and motor casing 7. The motor and the pump have a single common shaft 8 supported in suitable bearings in casing 5 and member 6. The shaft has a bore 8a extending from the closure end with suitable cross bores and grooves through which lubricant may be conducted to the bearings and other moving parts of both the pump and

the motor. The lower portions of both pump casing 5 and motor casing 7 provide a reservoir for lubricant which is maintained at a sufficient level to cover at least the lower portion of the 5 abutment plate 9 which is maintained in contact with piston 10 of the pump by springs 11. The pump has a single fluid inlet connection 12 (Figs. 2 and 3) and a single outlet connection 13 (Figs. 3 and 4). Since specific forms of pump and mo- 10 tor are not essential to the present invention, further description of pump A and motor B is omitted.

Fig. 3 illustrates diagrammatically one method of connecting a pump, or the pump unit il- 15 lustrated in Fig. 1, into a closed cycle refrigerating system utilizing as a working substance a lubricant in solution with a volatile liquid. The outlet 13 of the pump is connected to a condenser *x* where heat is extracted from the hot vapors 20 issuing from the pump and whence condensate is fed through an expansion device *y* into an evaporator *z* connected to inlet 12 of the pump. Evapo- 25 rator *z* is arranged to effect concentration of the lubricant solution in accordance with the process described in my aforementioned patent and may be of the form disclosed in my copending application Serial No. 151,671, filed November 30, 1926, now Patent No. 1,769,017 issued July 1, 1930.

Since the temperature of the pump will vary 30 with changes in environing temperature, and especially when it is arranged for intermittent operation as in automatically controlled refrigerating systems, it is highly important that lubricant within the pump be maintained at its proper viscosity so that there will not be undue wear of 35 working parts and so that the pump will operate with proper efficiency. To this end it is essential that the hot refrigerant vapor pass as quickly as possible to condenser *x* and be kept out of contact with the reservoir of lubricant in the motor 40 pump unit. Moreover, the level of lubricant in the reservoir must be maintained by separating and trapping out the entrained lubricant in the discharge of the pump.

In accordance with the present invention, the 45 separating apparatus is confined wholly within the pump structure. From the pump, whatever its form or construction, issues as through a short passage 14 a stream of hot vapor, laden with 50 drops of liquid by the churning action of the piston, valves and other moving parts. The vapor consists of a mixture of refrigerant and oil vapors with the oil vapor constituting only a small percentage of the total because the oil vapor's tension is much lower than that of the refrigerant. 55 The hot liquid consists of a solution of refrigerant in oil wherein for the same reason the proportion of oil is greatly in excess of the refrigerant. The proportions of oil and refrigerant in 60 both the vapor and liquid depend wholly upon the temperature and pressure if constant, or upon the rate of change if the temperature and pressure vary. The separating means about to be described are arranged to function so that the drops 65 of liquid may be caused to separate from the vapor without substantial change in the relative proportions of oil and refrigerant with the result that the liquid will remain nearly all lubricant.

Upon issuing from passage 14, the stream of 70 vapor and suspended lubricant passes a check or discharge valve 15 supported in a valve block 15a into a discharge chamber 16 which may be partly full of lubricant solution to muffle the sound of discharge. The vapor and suspended oil pass 75 through chamber 16 upwardly through a conduit

17 provided with a flaring mouth 17a which directs the same against one or more baffles 18 and separators 19 in a separating chamber 20. The separating means may be of any well known type but are indicated as in the form of baffle plates and screens respectively. The separated lubricant falls down around conduit 17 and fills a trap 21 whence it overflows into a chamber 22 into which the bored end of shaft 8 extends so that the separated lubricant fills bore 8a and the lubricant is distributed to the bearings and working parts of the motor and pump. Any excess of lubricant in chamber 22 is conducted by a passage 23 (Figs. 2, 3, and 4) into the motor chamber of the motor pump unit, where it drops into the reservoir of lubricant in the base of the unit whence it leaks back into the compression space around the sliding member 9.

For convenience of manufacture and assembly, the conduit 17 between discharge chamber 16 and separating chamber 20, and the trap 21 which seals the separating chamber from the passage for separated lubricant, may be combined in a single insert unit formed of sheet material as shown in Fig. 4. The lower part of this insert has 100 double walls in tight engagement which serve to seal the opening between chamber 22 of the lubricant passage and discharge chamber 16; thereabove these walls diverge, the inner wall forming the conduit 17 for the discharge and the 105 outer arranged in spaced relation with the inner wall to form the annular chamber of the liquid seal or trap 21. Still another wall member 24 serves as a bushing and seal for the opening between separating chamber 20 and lubricant 110 chamber 22 and extends between the spaced walls of the trap chamber 21 and well down toward the bottom of the same so that the separated lubricant from chamber 20 must take a tortuous path through trap 21 to 115 reach chamber 22, the lubricant retained in the trap chamber forming a liquid seal. It is thus apparent that while chambers 16, 22, and 20 provide an ascending series as indicated at Fig. 3, the 120 insert member just described serves directly to connect chambers 16 and 20 and then to provide a connection for liquid only between chambers 20 and 22 and a barrier against the passage of the gasses and vapors in chamber 20.

It is to be particularly noted that the body of 125 lubricant in the main reservoir in the base of the motor pump unit is sealed off from any bodies of lubricant in discharge chambers 16 and 20 by the trap 21 so that hot vapor from the first named chambers cannot enter the main casing of the 130 unit but can only go on through the separating chamber 20 and outlet connection 13 to the condenser. This is an essential part of the invention. If the hot vapor were to be brought back into contact with other parts of the housing, condensation would result not only in thinning out the 135 lubricant but in robbing the refrigerating evaporator *z* of its refrigerant, especially when the motor pump is cool. In carrying out the invention it is further advisable that the mass and the capacity of separating chamber 20 and the connection thereto, including chamber 16 and conduit 17, be kept low and out of heat exchanging relation with the pump so far as possible. For this 140 purpose these chambers are provided in the small closure member 6 at one end of the motor pump unit.

While the invention is herein described in what is now considered to be a preferred form, it is to be understood that the invention is not restricted 150

to the exact details thereof but covers all changes, modifications, and adaptations within the scope of the appended claims.

I claim as my invention:

- 5 1. A pump for use in heat transforming systems comprising a casing providing a lubricant reservoir, a discharge chamber and a separating chamber in superposition, baffle means in said last named chamber for facilitating the separation of vapor from lubricant entrained therewith, a passage leading from said separating chamber to the working parts of said pump and to said reservoir, said passage determining the quantity of lubricant retained in said separating chamber, and means in said passage continuously providing a liquid seal to prevent vapor from passing therethrough. 80
- 10 2. A pump for use in heat transforming systems comprising a casing providing a lubricant reservoir, a discharge chamber and a separating chamber in superposition, baffle means in said last named chamber for facilitating the separation of vapor from lubricant entrained therewith, a passage leading from said separating chamber to the working parts of said pump and to said reservoir, and means disposed between said chambers for interconnecting the same and for continuously providing a liquid seal between said discharge chamber and said passage. 85
- 15 3. A pump for use in heat transforming systems comprising a casing providing a lubricant reservoir, a discharge chamber and a separating chamber, a passage leading from said separating chamber to the working parts of said pump and to said reservoir, and an insert between said chambers providing a direct connection therebe- 90
- 20 4. A pump for use in heat transforming systems comprising a casing providing a lubricant reservoir, a discharge chamber and a separating chamber in superposition, baffle means in said last named chamber for facilitating the separation of vapor from lubricant entrained therewith, a passage leading from said separating chamber to the working parts of said pump and to said reservoir, and a combined conduit and trap member interposed between said chambers to interconnect the same and to provide a liquid seal in the connection between said separating chamber and said passage, said member being formed centrally and axially as a conduit between said chambers and having an outwardly flared end directly beneath said baffle means. 95
- 25 5. In a heat transforming apparatus, a pump, an electric motor for operating said pump, said pump and motor having a common shaft and being totally enclosed to form a sealed motor pump unit, the lower part of the inclosure of both said motor and pump forming a reservoir for lubricant, passages for conducting lubricant to the bearings and moving parts of both said motor and pump including a bore in said shaft, and means wholly within said unit including superposed discharge and separating chambers for separating and trapping out of the discharge stream of the pump the entrained lubricant, for feeding the same to said passages, and for conducting the excess to said reservoir. 100
- 30 105
- 35 110
